MESNE ASSIGNMENTS, TO WHITING & DAVIS COMPANY, OF PLAINVILLE, MASSA-
CHUSETTS, A CORPORATION OF MASSACHUSETTS.

HANDBAG.

1,367,207.

Specification of Letters Patent. Patented Feb. 1, 1921.

Application filed April 7, 1919. Serial No. 288,058.

To all whom it may concern:

Be it known that I, HARRY BRADLEY ROWAN, a citizen of the United States, residing at North Attleboro, in the county of Bristol, State of Massachusetts, have invented certain new and useful Improvements in Handbags; and I do hereby declare the following to be a full, clear, and exact description of the invention, such as will enable others skilled in the art to which it appertains to make and use the same.

This invention relates to hand bags of the type consisting of a frame formed of two U-shaped frame members which are hinged together at their ends and pieces of fabric which are united to the members of the frame and to each other below the frame. The object of the invention is to effect an improvement in the construction of such a hand bag by which a more attractive appearance is produced. The invention is of utility in hand bags of various types but it is of especial value in hand bags wherein the fabric consists of metallic link mesh.

In recent years the types of hand bags which have been most popular are those of considerable length relative to their width and the side lines of such bags are characterized by flowing graceful curves. In all such bags as heretofore constructed, however, there have been interruptions in the side contour lines of the bag immediately at the ends of the frame and the interruptions or jogs occurring at these points have been considered a necessary incident of the construction of the bag and the means employed for securing the fabric to the frame.

The present invention involves the provision of an improved construction for the members of the frame for such a bag whereby the outer edges of the fabric below the frame aline with the outer edges of the frame so that the bag as a whole has side contour lines which are unbroken and the appearance of the bag is therefore much enhanced. This desirable result is attained by a peculiar shape given to the grooves or recesses in the outer sides of the members of the frame extending along the inner edges of the members. Each of the frame-members is provided with a groove or recess in which the edge of the piece of fabric is secured. In accordance with this inven-

tion, the wall of this recess or groove is tapered or inclined outwardly at the ends 55 of the frame-member, preferably to such extent that at the extreme ends of the frame-member the groove or recess extends all the way across the front face of the member. In securing the fabric in this recess, the edge 60 of the fabric follows the wall of the recess so that at the ends of the frame-member, the edges of the fabric are in substantial alinement with the outer edge of the frame-member. This makes the outside contour 65 lines of the bag free from interruptions or jogs at the ends of the frame-members. The groove or recess preferably extends throughout the length of the frame-member, but if desired, it may only extend through the end 70 portions thereof.

The construction herein referred to will be better understood by reference to the drawing annexed hereto. In this drawing, Figure 1 is an elevation of a bag constructed 75 in accordance with the invention; Fig. 2 is an elevation of the frame showing the recess therein; Fig. 3 is a section on line 3—3 of Fig. 1; Fig. 4 is a transverse section on line 4—4 of Fig. 1; and Fig. 5 is a view similar 80 to Fig. 2 and illustrating a modification.

Referring to the drawing, the bag consists of a frame formed from two U-shaped frame-members 5 and 6 which are hinged together at their ends as indicated at 7. 85 The bag is completed by two sheets of fabric 8 and 9, preferably link-mesh fabric, which are secured to the two frame-members 5 and 6 and below the frame have their edges secured together.

Each of the frame-members 5 and 6 has a groove or recess in the outer side thereof and extending along the entire length of its inner edge. This recess is indicated at 10 in Fig. 2. It is of substantially constant 95 depth throughout the major portion of its length, that is, throughout the portion lying intermediate the end portions of the frame-member. But near the ends of the frame-member the recess widens, its bounding wall 100 being inclined outwardly toward the outer edge of the frame-member as is indicated at 11. At the extreme ends of the frame-member, the wall of the recess practically coincides with the outer edge of the frame- 105 member as is indicated in Figs. 1 and 2.

The upper portions of the pieces of fabric 8 and 9 are shaped to correspond with the shape of the frame and each of these pieces is secured to its frame-member with 5 its edge lying in the groove or recess 10. A spiral wire of a size corresponding to the size of the rings of the mesh is secured within the groove or recess 10 as is shown at 12, as by soldering or welding each convolution 10 of these spirals to the walls of the recess 10, and the piece of mesh is secured to this spiral by employing a second spiral 13 which is linked with the edge rings of the 15 piece of mesh and the convolutions of the spiral 12.

It will be noted, particularly on examination of Fig. 1, that the side contour lines of the completed bag are unbroken at the ends of the frame. This is due to the fact that 20 the recess or groove 10 in each frame-member is increased in depth by inclining its bounding wall outwardly toward the ends of the frame, the inclination being such that at the extreme ends of the frame the 25 bounding wall of the groove extends out to the outer edge of the frame. By reason of this inclination of the wall of the recess, the side edges of the fabric immediately below the frame are in alinement with the outer 30 edges of the frame. This gives to the completed bag a far more graceful appearance as it perfects the effort of the designer in giving to the bag its elongated shape and side contour lines which are characterized 35 by long flowing curves or extended vertical lines.

Fig. 5 illustrates a slight modification of the construction shown in Figs. 1, 2 and 3. The recesses which receive the edge portions 40 of the pieces of fabric are formed in the end portions of the frame-members but do not extend throughout the entire length of the members. Intermediate these end portions 45 of the frame members, the edges of the pieces of fabric are secured to the inner walls of the frame-members.

I claim:

1. A hand bag having a frame consisting of two frame-members hinged together at 50 their ends, each frame-member having its end portions recessed on the outer faces thereof, the recesses being of such width at the ends of the frame-members that they extend entirely across the outer faces of the 55 frame-members to points adjacent to the outer edges of the frame-members, spiral wires extending along the frame-members and having their convolutions secured to the frame-members, said spiral wires lying in 60 the recesses at the ends of the frame-members and extending along the bounding walls of the recesses, and pieces of mesh secured

to the spiral wires and secured together beyond the ends of the frame.

2. A hand bag having a frame consisting 65 of two frame-members which are hinged together at their ends, each of the frame-members having a recess extending along the inner edge of its outer side and the wall of the recess being inclined outwardly toward 70 and in close proximity to the outer edge of the frame-member near the ends of the frame-member, spiral wires extending along the frame-members and having their convolutions secured to the frame-members, said 75 spiral wires lying in the recesses at the ends of the frame-members and extending along the bounding walls of the recesses, and pieces of mesh secured to the spiral wires and secured together beyond the ends of the 80 frame.

3. A hand bag having a frame consisting of two frame-members which are hinged together at their ends, each of the frame-members having a recess extending along 85 the entire length of the inner edge of its outer side and the bounding wall of the recess being inclined outwardly near its ends so that at the extreme ends of the frame-member said bounding wall coincides with 90 the outer edge of the frame-member, a spiral wire lying in the recess in each frame-member close to the bounding wall of the recess and having its convolutions secured to the frame-member, and pieces of mesh secured 95 to the spiral wires and secured together beyond the ends of the frame.

4. A hand bag comprising a frame consisting of two hinged frame members, a groove along the inner edge of the outer 100 face of each of the frame members, this groove increasing in width toward the hinged ends of the frame member until, at these ends, its width is that of the frame members in these grooves and forming a 105 bag, the outer edges of which are in substantial alinement with the outer edges of the frame members.

5. A hand bag comprising a pair of substantially U-shaped frame members hinged together at the extremities of their arms, a groove along the inner edges of the outer faces of these frame member arms, which groove increases in width toward the hinged 115 ends of the arms, until, at these ends, its width is that of the face of the arms themselves, and a fabric united in the groove to the frame members and forming a bag which envelops the hinges of frame members save at their outer extremity.

In testimony whereof I affix my signature.

HARRY BRADLEY ROWAN.
